UNITED STATES PATENT OFFICE.

RAYMOND L. HICKMAN, OF PORTLAND, OREGON.

STOVE-LID LIFTER.

1,131,517.

Specification of Letters Patent.

Patented Mar. 9, 1915.

Application filed April 7, 1914. Serial No. 830,241.

To all whom it may concern:

Be it known that I, RAYMOND L. HICKMAN, a citizen of the United States, residing at Portland, in the county of Multnomah 5 and State of Oregon, have invented new and useful Improvements in Stove-Lid Lifters, of which the following is a specification.

This invention is directed to improvements in stove lid lifters and has for its 10 primary object the provision of a device of this character whereby the stove lid or other article under its own weight will in elevated position be effectively clamped between the jaws of the lifter, thus reducing to a minimum 15 the possibility of the lid dislodging itself from the jaws with a consequent dropping of the same.

I further aim to provide a device of the above mentioned character including a relatively 20 fixed and movable jaw with means operating to retain the jaws normally separated.

Other objects of the invention will appear 25 as the following description is read in connection with the accompanying drawing, the invention residing in the specific construction, combination and arrangement of parts hereinafter more fully described.

In the drawing forming a part of this 30 application, like numerals of reference indicate similar parts in the several views, and in which;

Figure 1 is a perspective view of the device. Fig. 2 is a side elevation showing the 35 jaws in operative position. Fig. 3 is a bottom plan view. Fig. 4 is a sectional view taken on line *a-a* of Fig. 1.

The invention contemplates the provision 40 of a device for the above mentioned purpose and consists of a sectional handle A, the inner and outer sections 5 and 6 respectively of which are pivotally connected as at 7.

The inner section comprises a relatively 45 broad base or bearing surface 8 and projecting rearwardly therefrom are spaced parallel members 9. Formed integrally therewith and rising from the upper edges of the members 9 immediately above the base 8 are spaced pivot ears 10 between 50 which is freely pivoted the jaw 11 which is movable relatively with respect to the fixed jaw 12 which extends forwardly and centrally from the base 8.

The outer section 6 comprises a hand gripping 55 portion 13 and projecting forwardly and centrally therefrom is a lever extension

14 which is pivotally mounted between the members 9 as shown at 7. The forward end of the lever extension 14 is provided with spaced lugs 15 formed by the provision of a 60 notch or recess 16 for the reception of the tail portion 18 of the jaw 11, thus causing the lugs 15 to engage the upper and lower surfaces of the tail portion 18 of the jaw 11 to move the latter to open and closed position on movement of the lever extension 14 on its pivot 7 in opposite directions. The upper surface of the base 8 is beveled rearwardly from a point adjacent the pivot ears 10, as is also the under surface of the tail 65 portion 18 of the jaw 11 to provide for the pivoted movement between the jaw and lever which is essential to a successful operation of the device. The inner end of the hand gripping portion 13 at the opposite side of the 70 lever extension 14 is formed with semicircular recesses 19 for the reception of the rounded end portions 20 of the members 9 whereby slight pivotal movement between the sections 5 and 6 is provided for. 75

In use the jaw 12 is inserted in the usual socket formed in the stove lid, and the section 5 obviously held against movement. Now when pressure is brought to bear on the outer section 6 in the act of lifting the lid, 80 the outer section is caused to move upon its pivot 7, thus raising the lever 14, which in turn engages the tail extension 18 of the jaw 11 and moves the latter to operative or closed position. With the tool constructed 85 and operating in the above described manner it is manifest that the heavier the lid or article to be lifted the more effectively the same is clamped between the jaws. 90

With a view of automatically returning 95 the lever to its normal position when the tool is disengaged from the lid, and consequently returning and holding the jaw 11 normally open, I employ a leaf spring 21 secured at one end to and adjacent the inner 100 end of the outer section 6 and having its body portion yieldably bearing against the inner section 5. By reason of this arrangement it is manifest that the lifter or jaws support the lid under tension of the spring, 105 and when the device is relieved of the weight of the article supported thereby, the spring operates to reverse the pivotal movement of the outer section, thus lowering the lever 14 which in turn moves said jaw 11 to 110 open position.

As will be noted the base portion 8 extends

rearwardly of the free end of the lever 14 and serves in the capacity of an abutment therefor to limit the movement of the latter in one direction.

5 From the foregoing description when considered in connection with the accompanying drawing, it is believed that the nature and advantages of the invention will be readily understood without requiring further explanation and therefore the same has been omitted. However I desire to have it understood that while I have shown and described the preferred embodiment of my invention various changes may be made in the 10 construction and arrangement of parts within the scope of the appended claim without departing from the spirit of the invention.

What I claim is:—

20 A device of the class described comprising an inner and outer section, said inner section having a base and spaced parallel members

projecting therefrom, a fixed jaw formed on said base, a movable jaw pivoted on said inner section above the fixed jaw, a lever extension formed on the outer section and pivotally connected between said parallel members, the free end of said lever engaging said movable jaw for operating the same and adapted to abut said base to limit the 25 movement of said lever in one direction, and a flat spring secured to said outer section and engaging said inner section to retain said lever positioned between said parallel members flush with the opposite edges thereof and to retain said jaws normally separated.

25 In testimony whereof I affix my signature in presence of two witnesses.

RAYMOND L. HICKMAN.
